UNITED STATES PATENT OFFICE.

ALBERT C. BARLEY, OF STREATOR, ILLINOIS.

DESIGN FOR A REAR AUTOMOBILE-WHEEL FENDER.

51,748.

Specification for Design.

Patented Feb. 12, 1918.

Application filed November 10, 1916. Serial No. 130,650. Term of patent 7 years.

To all whom it may concern:

Be it known that I, ALBERT C. BARLEY, a citizen of the United States, residing at Streator, in the county of La Salle and State of Illinois, have invented a new, original, and ornamental Design for Rear Automobile-Wheel Fenders, of which the following is a specification, reference being had to the accompanying drawing, forming part thereof.

Figure 1 is a side elevation, and Fig. 2 is a rear elevation of the fenders, showing my new design.

I claim:

The ornamental design for a rear automobile wheel fender, as shown.

ALBERT C. BARLEY.
